UNITED STATES PATENT OFFICE.

EDWARD H. ANGIER, OF QUINCY, MASSACHUSETTS.

COMPOSITE SHEET.

1,227,520.

Specification of Letters Patent. Patented May 22, 1917.

Application filed March 1, 1912. Serial No. 680,845.

To all whom it may concern:

Be it known that I, EDWARD H. ANGIER, a citizen of the United States, and a resident of Quincy, county of Norfolk, and State of 5 Massachusetts, (whose post-office address is Quincy, Massachusetts,) have invented an Improvement in Composite Sheets, of which the following description, in connection with the accompanying drawings, is a specification, like characters on the drawings representing like parts.

This invention relates to composite sheets used for packaging and other purposes.

The character of the invention may be 15 best understood by reference to the following description of an illustrative embodiment thereof shown in the accompanying drawing, wherein:

Figure 1 is a plan view of one face of a 20 portion of a composite sheet having parts of some of the layers thereof broken away to disclose the character of other layers;

Fig. 2 is a reverse view of the sheet shown in Fig. 1; and

Fig. 3 is a section taken on line 3—3 of Fig. 1.

Referring to the drawing, the illustrative composite sheet there shown as embodying the invention comprises a sheet-like layer 5 of Manila paper or other suitable material having on one face thereof a coating layer 7 of glue, or other appropriate adhesive.

On the opposite face of said sheet-like layer and in adhesive engagement therewith 35 is a water-proof layer 9, such, for example as black asphaltum, which is inherently flexible and will not crack when the sheet is bent or folded.

The asphaltum used is somewhat sticky. 40 To prevent articles from adhering thereto and to prevent any possibility of the asphaltum being scraped from the paper layer and becoming ineffective to insulate the paper layer from water, there is provided a 45 wear resisting protective layer 11 shown herein as a woven and preferably somewhat open mesh cotton cloth although it will be understood that other fabrics or textile materials might be used if desired. The 50 threads or fibers of the textile layer applied to the flexible asphaltum layer preferably are embedded somewhat therein so as to be securely retained thereto, and at the same time project from the face of said layer and 55 constitute an effective wear resisting protective layer.

A composite sheet such as described composed of the combined layers of different materials of different qualities presents a very advantageous construction. The Manila paper presents a strong foundation layer; the asphalt layer prevents any loss of the strength of the paper layer by softening from moisture, unites the fabric and paper layers and prevents said asphalt layer from 60 becoming scraped off, and the adhesive coating on the paper layer enables the sheet to be readily placed in adhesive engagement with any article merely on moistening said face and pressing the sheet to such article. 65

In some instances the water-proof and fabric layers may both be extended beyond one or more edges of the paper layer to provide strong, water-proof margins as at 13. The adhesive character of the water-proof 70 layer will enable it to be placed in adhesive engagement with an article to constitute an effective water-proof seal to prevent ingress of moisture to the adhesive face of the paper layer, and contribute to the maintenance of the adhesive engagement thereof to the article to which it is attached.

To prevent the edges from being pulled up or separated from the article to which they are attached, the fabric layer may be extended beyond the other layers to present a thin margin or margins as at 15, which may be secured to the article by glue or other suitable adhesive.

A composite sheet of the character described may be produced in wide, narrow ribbon-like strips or in other forms convenient for commercial use. When cut into long narrow strips it may be employed for sealing paper boxes or packages, for strengthening the corners or other parts thereof, for binding or wrapping purposes and various other uses as desired. The sheet may also be employed to constitute a complete protective covering for a bag or a corrugated paper box which is liable to be exposed to moist conditions. The sheet also lends itself advantageously as a lining for boxes, bags or other receivers.

Having described illustrative embodiments of the invention without limiting the same thereto, what I claim as new and desire to secure by Letters Patent is:

1. A composite sheet comprising a sheet-like layer having an adhesive coating on one face thereof; a water-proof layer on the opposite face thereof; and an outer woven

fabric layer for protecting said water-proof layer, all of said layers being secured together and said water-proof layer and said fabric layer being extended beyond said sheet-like layer to provide a water-proof edge protective margin exposed beyond said sheet-like layer.

2. A composite sheet comprising a sheet-like layer having an adhesive coating on one face thereof and a water-proof layer on the opposite face thereof; and a textile protective layer for said water-proof layer, all of said layers being secured together and said textile layer being extended beyond said other layers and presenting both surfaces exposed to provide a protective margin.

3. A composite sheet comprising a sheet-like layer 5 having an outer adhesive coating 7 on a face thereof; a waterproof layer 9 on the opposite face thereof; and an outer textile layer 11 for protecting said

waterproof layer, all of said layers being secured together and one of said layers being extended beyond the others to provide an edge protective margin having an exposed surface. 25

4. A composite sheet comprising a sheet-like layer having an outer adhesive layer on one face thereof; a waterproof layer on the opposite face thereof; and an outer textile 30 layer for protecting said waterproof layer, all of said layers being secured together, two of said layers being extended beyond the other to provide an edge-protective margin having an exposed surface. 35

In testimony whereof, I have signed my name to this specification, in the presence of two subscribing witnesses.

EDWARD H. ANGIER.
